UNITED STATES PATENT OFFICE.

PEDRO SALAVERRI TELLECHEA, OF SAN SABASTIAN, SPAIN.

FURNACE AND STEAM-BOILER FIRE-BOX SYSTEM.

Application filed March 14, 1927, Serial No. 175,061, and in Spain February 15, 1927.

The present invention refers to furnace and steam-boiler fire-box systems and especially refers to a process for doing away with the grating of such fire-box, which, up to present, 5 has been looked upon as being an indispensable element in the production of the draught necessary to effect a perfect burning of the fuel.

Apart from effecting an advantage of a 10 saving nature, which, in itself is of sufficient importance, and of realizing a technical advance in industry, the invention affords the outstanding advantage of being able to make use of any kind of fuel together with the suppression of smoke. In accordance with the 15 present process, both coal and residues thereof as well as sawdust, furze or any other low cost fuel may be used, all of which will obtain the maximum calorific yield up to its being 20 entirely consumed.

The attached drawings show, by way of example, a form of carrying the invention into effect and in them:—

Fig. 1 shows the section of a furnace drawn 25 up in accordance with the invention.

Fig. 2 shows a plan detail of the same.

Fig. 3 shows a front view of a furnace made as per the invention; and

Fig. 4 shows a detail of one of the plates 30 and its operating lever.

As will be seen from the drawings, a fire-box made in accordance with the invention is composed of the following elements:

It being supposed (see Fig. 1) that the 35 necessary heating has to be supplied to a boiler or furnace 1, the latter will be built with the front wall of fireproof or other suitable material 2. On this wall is mounted a sliding door 4 operated at 3 by any known 40 means allowing of its being gradually raised or lowered to given distances and leaving an opening 4 for the purposes to be stated later.

The fire-box grating is formed by a flooring 45 entirely composed of plates 7 laid in echelon one overlapping the other and which, under normal conditions, furnish a flooring completely joined and sealed on which the coal thrown in through hopper 5 will rest, the 50 hopper being provided with a sliding door 6 or something similar thereto.

These plates 7 are susceptible of being operated in the direction shown by the dotted line of Fig. 1 by means of levers 8 which raise

same and allow them to pivot on axle 12 which 55 maintains the plates fixed at one point, and the pivot 11 allowing of the articulation of said lever on the plate. Each lever 8 has notches 14 made therein which allow of its being hooked into a fixed position onto rods 60 or projecting points 13 provided in the inner walls of the fire-box.

The working is as follows:—

Fuel is thrown into hopper 5 and, by reason of the sloping position of said hopper, 65 it is distributed along the surface of the plates. Once the coal is inside, the hopper is closed by sliding door 6, the fuel then being set on fire at the most convenient point. As will be easily understood from this, the sliding door 4 of the fire-box serves to regulate 70 the thickness of the fuel layer and as an inlet for same through space 4.

Once the fuel is set on fire, any one of the plates is raised (in case of a strong combustion being required, several could be lifted) 75 and for this reason the following effect will be produced:—

There will be started a draught directly to the chimney of the fire-box coming through 80 the space made by the plate being raised and said draught will follow the direction shown by arrows in Fig. 1. The force of this draught will have the same effect as a blowpipe on the burning fuel, the flame of this so-called blowpipe being applied directly on 85 the wall of the boiler adjacent to the fire-box.

A successive working of the plates will permit the regulation of the intensity of the combustion and the progressive or simultaneous 90 burning of the whole fuel layer, thereby realizing a perfect graduation of the intensity of the fire, and an absolute regulation of the fuel being burned.

On the other hand, the direct action of the 95 air, permits the utilization of any kind of fuel without fear of obstruction or of defects in the fuel due to the constant activity of the draught given to the combustion process.

It will be understood from what has been 100 stated, that the invention will still continue to exist even in the case of different means application being adopted necessary to the exigencies of the cases that may appear in practice, such as the application of the invention to industrial fire-boxes, furnaces, moving or stationary steam-boilers, heating boilers etc. Also the elements employed to carry the 105

invention into effect could be made of any kind of material adequate for the purpose in each case.

I claim:

5 1. A furnace comprising a fuel-receiving hopper, a plurality of normally inclined plates adjacent the outlet of said hopper and combining to form the grate of the furnace, means for regulating the passage of fuel from
10 said hopper to said grate, and means for separately varying the inclination of each of said plates.

2. A furnace comprising a fuel-receiving hopper, a plurality of plates adjacent the outlet of said hopper, said plates being normally inclined away from said outlet and combining to form the grate of the furnace, operating
15 levers attached to said plates for separately

varying their inclination, and means for selectively supporting each of said operating levers in a plurality of positions.

3. A furnace comprising a fuel-receiving hopper, a plurality of normally inclined and pivotally supported plates constituting the grate proper of the furnace, a notched lever 25 pivoted to each plate for individually varying its inclination, a rod engaging in the notches of each lever to support the associated plate in any adjusted position, and a sliding door disposed between said hopper and grate 30 and movable toward and away from said grate to regulate the passage of fuel from the hopper to the grate.

In testimony whereof I have affixed my signature.

PEDRO SALAVERRI TELLECHEA.
